US00D891972S

(12) United States Design Patent (10) Patent No.: US D891,972 S
 Leclerc (45) Date of Patent:  Aug. 4, 2020

(54) BRACELET

(71) Applicant: AB7 SANTÉ, Deyme (FR)
 (72) Inventor: Sophie Leclerc, Toulouse (FR)
 () Term: 15 Years
 (21) Appl. No.: 35/506,476
 (22) Filed: Sep. 26, 2018

(80) Hague Agreement Data

Int. Filing Date: Sep. 26, 2018
 Int. Reg. No.: DM/103387
 Int. Reg. Date: Sep. 26, 2018
 Int. Reg. Pub. Date: Mar. 29, 2019

(51) LOC (12) Cl. 11-01(52) U.S. Cl.USPC ..... D11/4; D24/187(58) Field of Classification Search
